Primary Examiner — Jennifer L Watkins*Assistant Examiner* — Christine Tucci(74) Attorney, Agent, or Firm — Rumit Ranjit Kanakia(57) CLAIM

The ornamental design for a shoe, as shown and described.

DESCRIPTION

FIG. 1 is a front perspective view of a shoe, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines crossing claimed surfaces depict portions of a shoe and form no part of the claim. The patterned surfaces encircled by broken lines on the outsole of the shoe form no part of the claim.

1 Claim, 6 Drawing Sheets(56)
